ABRADING MACHINE

Leon D. Alderman, Beverly, Mass., assignor to
 United Shoe Machinery Corporation, Borough
 of Flemington, N. J., a corporation of New
 Jersey

Application July 25, 1940, Serial No. 347,447

1 Claim. (Cl. 51—78)

This invention relates to abrading machines and is herein illustrated and described as embodied in a buffing machine of the type disclosed in United States Letters Patent No. 2,218,537, granted October 22, 1940, upon the application of Norwood H. Knowlton. Such machines are conveniently used for operation upon shoe parts, such as outsoles which are to be buffed on their grain surfaces prior to their attachment to shoes, or counters which are to be buffed first on one side and then on the other. Machines of the type under consideration include in their organization a buffing tool, means for feeding a work-piece past the buffing tool, and a device for holding the work-piece in engagement with the buffing tool during its progress past the tool.

It is an object of the present invention to provide a buffing machine with improved means for holding a work-piece in engagement with a buffing tool. As shown herein, the illustrated machine is provided with a plurality of resiliently yieldable fingers for slidably engaging a moving work-piece to press the work-piece against the buffing tool. In accordance with a feature of the invention, each of these fingers carries a replaceable work-engaging member of wire, the wire being bent to retain it in a hole formed in the finger. These wires serve to protect the ends of the fingers from damage by contact with the buffing tool; and the wires themselves may readily be replaced if damaged by such contact.

The invention will be best understood by reference to the following description, when taken in connection with the accompanying drawings of one specific embodiment thereof, while its scope will be more particularly pointed out in the appended claim.

Referring now to the accompanying drawings:

Fig. 1 is an end elevation showing the general organization of buffing tool, work-feeding means and presser member;

Fig. 2 is a view looking in the direction of the arrows on Fig. 1, showing the presser member and showing also the portion of the buffing roll in section along the line II—II of Fig. 1;

Fig. 3 is a sectional view along the line III—III of Fig. 4;

Fig. 4 is a detail view of the presser member; and

Fig. 5 is a sectional view taken along the line V—V of Fig. 4.

As shown in Fig. 1, the machine disclosed herein consists in its general organization of a buffing roll 140 having an abrasive cover 500 (Fig. 2), a work-feeding device 214, a work table 55

238, and a feed plate 232 having a smooth under surface for pressing the work-piece into the resilient material of the feeding device just prior to the engagement of the work-piece with the buffing roll. All of the parts above-mentioned are similar to the parts similarly numbered in Letters Patent No. 2,218,537 above referred to, to which reference may be had for a more complete understanding of their detailed construction. As described in that application, the work-feeding device comprises a plurality of rubber feed belts mounted upon individual pulleys having parallel axes, but with the axis of each pulley slightly displaced from that of its neighbor and oblique to the axis of the buffing roll to introduce an axial component of movement between the work and the buffing roll for the purpose of eliminating scratch marks upon the work. This oblique relation, however, is of no importance in connection with the present invention. The feed belts of the Knowlton machine may therefore for present purposes be considered the equivalent of an ordinary feed rubber covered roll 214 which is shown in the present drawings. 15 In place of the presser member 284 of the machine disclosed in the above-mentioned Letters Patent No. 2,218,537, the present machine is provided with an improved presser member 600 (Figs. 1 and 2) which is carried by a transverse frame member 153 which corresponds to the similar member of the Knowlton machine.

For supporting the presser 600 upon the frame member 153, there is provided a transversely extending bracket 602 which is secured directly to the frame member by bolts 604 extending through vertical slots in the bracket 602 to accommodate heightwise adjustment of the presser. At each end of the bracket 602 is an inclined ear 606 to which is secured a plate 608 which constitutes the principal supporting structure of the presser member. The plate 608 is clamped upon the ear 606 by screws 610 passing through washers 612. Secured against the under face of the plate 608 by three screws 614 is a second plate 616. The screws 614 extend through slots 618 formed in the plate 608 to accommodate adjustment of the plate 616. A key 620 secured in the plate 616 and extending into a slot 622 in the plate 608, maintains the plate 616 in alignment. The adjustment of the plate 616 is effected by a screw 624 threaded into a block 626 which is secured to the plate 608 by screws 628. The screw 624 is held against endwise movement relatively to the plate 616 by a pair of collars 630 secured upon a smooth portion of the shank of the screw 624.

and engaging opposite surfaces of a plate 632 secured upon the plate 616 by screws 634. In order to lock the plate 616 against movement from adjusted position there is provided a screw 636 threaded through the block 626 and secured in fixed relation thereto by a lock nut 638. A pair of knurled nuts 640 and 642 adjustably threaded upon the screw 636 engage opposite faces of the plate 632 to hold the plate 616 in adjusted position. It is sometimes convenient to secure the nuts 640 and 642 in spaced relation upon the screw 624 by lock nuts or set screws, in which case the nut 640 is used as a stop to prevent adjustment toward the abrading roll closer than a predetermined clearance, and the nut 642 is used to determine a desired position of readjustment.

Secured to the under face of the plate 616 by screws 644 is a plate 646 having a flange 648 turned inwardly toward the plate 608. Interposed for transverse sliding movement between the plates 646 and 608 is a bar 650 extending substantially the length of the plate 646. As shown in Fig. 5, this bar is angular in cross section except at its end portions which are solid. Engaging each of the solid end portions of the bar 650 is the shouldered end portion of an adjustable supporting screw 652. Also interposed between the plates 646 and 608 and extending substantially the length of the bar 650 and resting upon one of the flanges thereof is a long block or pad 654 of sponge rubber. Secured to the under face of the plate 608 by screws 656 extending through spacer blocks 658 and at a locality beyond the flange 648 is a transverse retaining plate 660.

The presser fingers are mounted for longitudinal reciprocatory movement between the retaining plate 660 and the plate 608 and comprise a set of relatively wide fingers 662 (Fig. 3), the opposite edge portions of which engage guide slots 664 and 666 formed in the retaining plate 660 and plate 608 respectively, and also a set of relatively narrow fingers 668 arranged in alternate relation between the wide fingers. The narrow fingers are held against edgewise movement by engagement with the plates 660 and 608, and against transverse movement by engagement with the adjacent wide fingers. The inner end of each of the fingers 662, and also the inner end of each of the fingers 668, is provided with a foot 670 which abuts the pad 654 and is retained by interlocking engagement with the flange 648.

The outer end portion of each finger is in the form of a flange 672 suitably notched and bored to receive a work-engaging member 674 consist-

ing of a wire which is first introduced through the bore and is then bent to the form shown in Fig. 5 to retain it in position. The outer portions of the work-engaging members are smooth and engage the work with a minimum of friction. These wires are of a moderately hard wear-resistant steel, and may be readily and individually replaced if damaged by contact with the buffering tool; and it may be noted that they serve to protect the ends of the fingers 662 and 668 from such contact.

In the operation of the machine, a sole S (Figs. 1 and 2) passing between the work table 238 and the feed plate 232 is engaged by the feed roll 214 and thereby pressed against the feed plate 232 and the buffering roll 140. The presser fingers above-described deflect the sole upwardly and curve it partially around the buffering roll, prolonging the engagement of the sole with the buffering roll under a pressure which is relatively light, as compared with the initial pressure exerted by the feed member 214, to obtain a smooth finish. It will be observed, with reference to Fig. 2, that, however irregular the work piece may be in cross section owing to its edges having been skived, the fingers 662 and 668 will yield individually to press each portion of the sole with approximately equal pressure against the abrading surface of the buffering roll. The pad 654, by reason of the particularly resilient quality of sponge rubber, will yield locally in such a way as to act almost independently upon adjacent presser fingers. The degree of compression of the pad may be adjusted by tightening the screws 652. The normal or extended position of the presser finger may be varied from or toward the buffering roll to accommodate work-pieces of greater or less thickness by varying the position of the flange 648 through the adjustment affected by the screw 624. Such adjustment of the position of the presser finger is only necessary however for extreme thicknesses, owing to the highly resilient nature of the sponge rubber pad.

Having thus described my invention, what I claim as new and desire to secure by Letters Patent of the United States is:

A work-pressing finger for use in abrading machines, comprising a finger-like member adapted to press a moving work-piece against an abrading tool, and a replaceable work-engaging member of wire, said finger having a hole through which said wire passes, and said wire being bent to retain it in the hole.

LEON D. ALDERMAN.
